UNITED STATES PATENT OFFICE.

SOCRATES KEATS, OF TOESS, SWITZERLAND.

TOOL FOR TRIMMING SOLES.

SPECIFICATION forming part of Letters Patent No. 437,858, dated October 7, 1890.

Application filed May 1, 1889. Serial No. 309,177. (No model.) Patented in England February 3, 1885, No. 1,498.

To all whom it may concern:

Be it known that I, SOCRATES KEATS, of Toess, near Winterthur, Switzerland, have invented certain new and useful Improvements 5 in Edge-Setting and other Cutting Tools for Trimming Boots or Shoes, of which the following is a specification.

I have obtained British Letters Patent for the same, numbered 1,498, and dated February 3, 1885.

My invention consists in the novel combination of cutter-holders and cutters herein-after described and claimed.

In the accompanying drawings, Figure 1 shows in side elevation a compound cutting-tool, which is used for trimming the edges of soles, and commonly known as "edge-trimming," such tool being carried by a spindle projecting from the end of a driving-shaft. Fig. 2 is an inner end view, and Fig. 3 is an outer end view, of the compound cutting-tool, which is composed of two concentric holders, one fitting over the other and adjustable, so as to vary the width of cut according to the thickness of the sole to be operated upon. Figs. 4 and 5 show the two parts of the cutter detached from each other and drawn in cross-section, and Figs. 4^a and 5^a show one of the blades detached from their respective holders.

A, Fig. 1, is the spindle on which the tool is mounted.

B and C are the two parts of which the tool is composed. The part B is fitted with blades b, which make the square cut of the sole edge and also take off the burr on the inner or upper angle of the sole, and the part C is fitted with cutters c for taking off the burr on the outer or lower angle of the sole.

The holder B, which is screwed onto the end of the spindle A, consists of a hollow cylinder with one closed and one open end, such cylinder having parallel slots cut in its periphery extending from the edge of the open 45 to the closed part for the purpose of forming throats for the insertion of the blades b. This holder is formed with a taper annular flange b' on its inner end, which is intended to enter the crease of the boot or shoe and act as

a guide for facilitating the manipulation of the boot. These blades have upon them projecting taper teeth which enter and substantially conform to the annular guiding-flange b' for trimming the burr from the inner edge of the sole.

By reference to Fig. 2 it will be seen that the holder B is fitted with four cutters, the cutting-edges of which are ground so as to form a chamfering-edge at an obtuse angle to the main cutting or paring edge, as shown in the detached views, Fig. 4^a. These chamfering-edges stand up within the divided flange b', and, entering the crease of the boot, they act upon the adjacent edge of the sole and trim off the burr therefrom. The cutters b are made fast in their holder by clamping-screws b².

The stem of the holder B carries the holder C, and keyways are formed in both the spindle and the holder to receive a loose key c', which is locked by a binding-screw c², passed through the holder C. By this arrangement I secure the adjustment of the holder C relatively to the holder B to suit the varying thicknesses of sole to be trimmed. The holder C, it will be seen, carries two cutters c, which are inserted in spaces cut in the periphery of the holder, and are held in place by clamping-screws. These cutters are intended to take off the burr from the outer or lower angle of the sole, and for this purpose they are shaped as is best shown in the detached views, Fig. 5^a.

It will now be understood that this compound tool before being used must be adjusted to suit the thickness of the sole to be operated upon, as otherwise the burr of one angle only of the sole edge would be removed by its action.

Having now particularly described and ascertained the nature of my said invention and in what manner the same is to be performed, I declare that what I claim is—

In a rotary cutting-tool for trimming boots or shoes, the combination of a hollow slotted holder open at one end and provided round its open end with a divided taper annular guiding-flange, tangential profile-cutters se-

cured to the interior of said holder and provided with projecting taper teeth conforming substantially to the said flange and entering the divisions therein for producing a chamfering cut at the inner angle of the work, a second holder carried by and adjustable endwise on the first holder, and chamfering-cut-

ters mounted on said last-named holder for acting on the outer angle of the work, substantially as specified.

SOCRATES KEATS.
